UNITED STATES PATENT OFFICE.

GEORGE H. WILSON, OF UTICA, NEW YORK.

FOLDING COT-BED.

SPECIFICATION forming part of Letters Patent No. 409,262, dated August 20, 1889.

Application filed March 6, 1889. Serial No. 302,180½. (No model.)

To all whom it may concern:

Be it known that I, GEORGE H. WILSON, of Utica, in the county of Oneida and State of New York, have invented certain new and useful Improvements in Folding Cot-Beds; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to folding cot-beds; and the objects of my invention are, first, to provide a folding bolster for this class of beds which shall be automatically moved into position when the legs of the bed are extended and automatically folded down when the legs are turned up under the cot-frame; also, to provide means for retaining the legs in extended position and for straining the canvas bottom of the bed; and, finally, for firmly securing the edges of the canvas bottom to the side rails of the bed-frame in such manner as to prevent all possibility of tearing the fabric.

To the above purposes my invention consists in certain peculiar and novel features of construction and arrangement, as hereinafter described, and pointed out in the claims.

In order that my invention may be fully understood, I will proceed to describe it with reference to the accompanying drawings, in which similar letters of reference designate similar parts, and in which also—

Figure 1 is a side elevation of a cot-bed with my improvements applied thereto. Fig. 2 is an end elevation of the same looking at the head of the bed. Fig. 3 is a central longitudinal section of the bed shown in Fig. 1. Fig. 4 is a view showing the bed folded up. Fig. 5 is a cross-section of one of the side rails, showing the arrangement for securing the edges of the canvas bottom. Fig. 6 is an end view of one of the bolster-frames. Fig. 7 is a sectional view on the line A B of Fig. 3.

In the said drawings, 1 designates the side rails of the bed.

2 designates the pair of legs which support the head end of the bed, and 3 the pair of legs which support the foot end of the same, said

legs being pivoted at their upper ends to the inner sides of the rails 1, as shown at 1^a and 1^b, respectively. Between each pair of legs 1 and 2 are placed a series of folding braces, as best shown in Fig. 2. As will be seen by reference to this figure, two braces 3^a and 3^b are pivoted together at their inner ends midway between the two legs, and the outer ends of said braces are pivoted at 3^b and 3^c upon the upper parts of said legs. Two braces 4 and 5 are pivoted upon the lower parts of the legs at 4^a and 5^a, and the inner end of the brace 4 is pivoted upon the brace 5 at a point 5^b midway between the legs; but it will be observed that the brace 5 is longer than the brace 4 and extends beyond the point at which the brace 4 is connected to it. The extremity of this extended portion of brace 5 is pivoted in a slot 18, upon the opposite brace 3, at a point beyond its inner end, as shown. The result of this arrangement is that when the sides of the bed are separated the braces 3^b 3^a rest at their inner ends upon the upper side of the brace 5, and thus lock all of the braces and form a firm support for the legs while also tightly straining the canvas.

6 designates two bars which constitute the bolster-frame of the bed, and to which the upper or head portion of the canvas bottom is secured, as hereinafter more particularly described. These bars 6 are pivoted to the side rails 1 at the points 7, and are connected to the legs 2 by hooks 8, as best shown in Fig. 7, which engage or are pivoted in the legs at a point a little below where the leg is pivoted to the side rail. The straight portion or body 9 of hooks 8 is considerably elongated, and said body portions slide in grooves 10, which extend longitudinally of the bolster-frames 6. As the hook 8 engages the leg below its pivotal point, it is evident that as the leg is folded by turning on its pivot the shank of the hook 8 will be partially drawn out of the groove in the bolster-frame, and as it passes around the pivotal point of the leg and into line with the side rail the bolster-frame is automatically operated therewith and folded thereby. The washers 11 of the pivots 7 serve to retain the hook stems or bodies within the grooves 10. It will also be seen, by reference to Figs. 1 and 3, that the inner or lower ends

of bolster-frames 6 serve as braces to support the legs 2 when they are extended.

The legs 3 at the foot of the bed are braced when extended by bars 12, which are pivoted 5 at one end to the side rails 1, and which are connected to the legs 3 by hooks 14, working in longitudinal grooves in said bars 12, similarly to the hooks 9, before described, and retained in said grooves by staples 13. (See 10 Fig. 3.) It will be observed that when the legs 3 are extended the lower ends of the bars 12 serve as braces to support said legs.

In order to firmly secure the edges of the canvas bottom 15 (see Fig. 5) to the side rails 1, elongated dovetail grooves 16 are formed 15 in the sides of said rails, and the edges of the canvas bottoms are retained within said grooves by elongated metal strips 17, which are driven in endwise from the ends of the 20 grooves 16. A similar arrangement is employed in connection with the bolster-frames 6. The fabric bottom 15 in the construction shown extends in one piece from the foot of the cot to the head of the bolster-frame, al- 25 though it is evident that a separate piece of fabric might be used upon the bolster-frame.

It will thus be seen that a simple, strong, and durable form of cot-bed is produced, which is readily set up and folded, and that 30 the canvas bottom is securely held to the frame without being perforated, and consequently avoiding all possibility of rupturing or tearing the edges of the bottom. It will also be seen that the bolster-frame is auto-

45 matically raised and lowered by extending 35 and folding up the legs 2, and that the canvas bottom is equally strained throughout.

Having thus described my invention, what I claim as new, and desire to secure by Letters Patent, is—

40 1. In a cot-bed, the combination, with the oppositely-disposed legs, of the interlocking-braces 3^a, 3^d, 4, and 5, each of which is pivoted at one extremity to the legs and the braces 3^a and 3^d to each other, and 3^d having a slotted 45 opening 18, and the braces 4 and 5 pivoted to each other at 5^b, and the brace 5 engaging 3^a in the slotted opening therein, substantially as set forth.

2. In a cot-bed, the combination, with the 50 side rails and the folding legs, of the bolster-frames pivoted to the side rails, and hooks sliding in the bolster-frames and connecting the latter to the legs, substantially as described.

55 3. In a cot-bed, the combination, with the folding legs, of pivoted bars secured to the side rails and serving as braces for the legs, and hooks connecting the legs and bars and sliding in grooves in the latter, substantially 60 as described.

In witness whereof I have affixed my signature in presence of two witnesses.

GEO. H. WILSON.
